UNITED STATES PATENT OFFICE.

NINA H. PIFFARD-FRANCIS, OF NEW ROCHELLE, NEW YORK.

COLLAPSIBLE WINDOW GRILLE.

Application filed October 26, 1921. Serial No. 510,646.

To all whom it may concern:

Be it known that I, NINA H. PIFFARD-FRANCIS, a citizen of the United States, and a resident of New Rochelle, in the county of 5 Westchester and State of New York, have invented certain new and useful Improvements in Collapsible Window Grilles, of which the following is a specification.

My invention relates to an improvement 10 in the ornamentation of windows where the effect desired is produced by a frame dividing the surface of the window to the eye into small panes or divisions of any chosen ornamental shape each being separately set and 15 the object of the invention is to produce the desired ornamental effect without resorting to the troublesome and expensive method of setting each of a number of panels individually into the frame, as is done in windows 20 having what is known as leaded glass panels.

To carry out this invention I employ a frame the various members of which are suitably fastened together and arranged to produce to the eye the ornamental individual 25 panels desired, combined with means for setting said frame directly against the surface of the glass window pane and retaining it in position thereon, all as more particularly hereinafter described.

30 In carrying out my invention, the frame is by preference made collapsible although this is not necessary to the purposes of my invention and merely adds to the ease with which the same may be removed from position 35 against the surface of the pane to permit the cleaning of the latter. When, however, the frame is made collapsible, the individual panels or panel effect may readily be made to imitate diamond panes. Other 40 shapes of members, however, might be used to give variations in the ornamental shapes of the individual panels. In the illustration of the invention shown the center panel is a larger diamond surrounded by smaller 45 ones.

In the accompanying drawings:

Fig. 1 is a front elevation of a window furnished with a frame according to my invention to give the appearance of a window having numerous diamond-shaped panes each separately set in the usual manner.

Fig. 2 is a vertical section on the line 2—2.

Fig. 3 shows the frame partially collapsed 55 for withdrawal from position.

1 indicates the window sash and 2 a pane

of glass having a continuous, flat surface and permanently set or retained at its edges in said sash in any suitable way.

3 indicates the various members of the 60 frame which members are made of such thickness and are fastened together in such way as to permit the frame thus provided to set immediately against the surface of the pane, where it may be retained in position by the cleats or retaining pieces 4, the latter being however detachable or movable to allow the frame to be removed. The material of the members 3 is wood, metal or other suitable substance. For convenience 65 the individual members 3 may be hingedly connected together to form a collapsible frame which lays off the surface of the window into diamond-shaped panels although, as above indicated, each of said members 70 may be curved instead of being straight between the points of hinging. The manner of securing the members to one another at the crossing or junction point marking the corners or limits of the individual panels 75 may be of any desired character but attention should be paid to so constructing the frame as a whole as to permit the plane thereof as a whole to be applied closely to or in contact with the surface of the pane 2. 80

When the frame is thus constructed by hinging the strips together it may be readily partially collapsed as shown in Fig. 3, and, on re-application to the pane 2, may be spread out to fill the space marked by the 85 edges of said pane.

As will be seen, my invention affords a cheap and very inexpensive way of producing in a window already set the ornamental effect of a leaded window made of 90 a number of panes each having its own setting this effect being secured by reason of the fact that the frame, divided into panels, can be applied directly to the surface of the window pane. Also, as will be 95 seen, the window may be readily kept clean since the frame is readily removable by simply detaching the cleats or retaining pieces 4, 4. It will be understood that the members of the frame are of such size that when it is expanded from the position shown in Fig. 3, it will substantially completely fill the space bounded by the frame 1 in which the pane 2 is set.

What I claim as my invention is:—

1. The combination with a window sash or frame and a pane of glass having a

- continuous flat surface permanently set or retained at its edges in said sash, of a paneled frame applied directly in engagement with the flat surface of the window pane and 5 simulating by its panels the individual lights of a leaded window and means on the window sash or frame for detachably securing said paneled frame in position against the continuous surface of the window pane.
- 10 2. In an ornamental window, the combination with a window sash having a continuous pane of glass permanently set in it at its edges and a collapsible frame 15 simulating, when expanded, the diamonds or lozenges of a leaded glass window, said collapsible frame being made of thin strips
- hingedly secured together and filling the whole space in the window frame while expanded and applied directly against the face of the window pane and retaining pieces at the edges of the window sash for removably holding said frame of hinged members in direct contact with the surface of the window pane as and for the purpose described. 20 25

Signed at New York in the county of New York and State of New York this 24th day of October A. D. 1921.

NINA H. PIFFARD-FRANCIS.
